UNITED STATES PATENT OFFICE.

JOHN B. WARREN, OF NEW YORK, N. Y.

DESIGN FOR A DOLL.

Application filed April 8, 1926. Serial No. 17,214. Term of patent 14 years.

To all whom it may concern:

Be it known that I, JOHN B. WARREN, a citizen of the United States, residing at New York, in the county of New York and State of New York, have invented a new, original, and ornamental Design for Doll, of which the following is a specification, reference being had to the accompanying drawing, forming part thereof.

The figure is a perspective of a doll showing my new design.

I claim:

The ornamental design for a doll as shown. JOHN B. WARREN.
